SLASHER HOOD

Woolmer W. Myers, Taunton, Mass., assignor to
Wolverine Equipment Co., Cambridge, Mass., a
corporation of Massachusetts

Application January 24, 1945, Serial No. 574,395

6 Claims. (Cl. 98—115)

1

The present invention relates to slasher hoods and analogous drying equipment and has for its object to furnish improved means for preventing water or condensation from dripping on the yarns or other goods being dried. The improvements are particularly concerned with baffles so arranged in an enveloping hood as to permit free passage of vapor from the yarns in course of drying but also effectively prevent dripping of any condensate on the yarn, and with provisions by which the baffles may be conveniently mounted in position for use, removed for cleaning or other purposes, and replaced.

An illustrative embodiment of the invention is shown in the accompanying drawings and described in the following specification.

In the drawings:

Fig. 1 is a diagrammatic illustration in side elevation of a conventional slasher, and a partial side elevation and partial section of a hood for conducting away vapors, in which the novel characteristics of the invention are included;

Fig. 2 is a cross section of the hood taken on line 2—2 of Fig. 1 and shown on a larger scale, but contracted in width;

Fig. 3 is a longitudinal detail section taken on line 3—3 of Fig. 2;

Fig. 4 is a perspective view of one of the removable side plates of the hood.

In the diagrammatic representation of the standard slasher here shown, *a* represents the size box, *b* the steam heated large drier drum over which the yarns pass from the size box, *c* a guide roll which takes the yarns from the drier drum, and *d* the sheet of yarns for a warp employed in weaving, which passes around drums *b* and *c* in succession and thence to a beam, not shown, on which it is ultimately wound. The invention is embodied in a hood which overlies the size box and drums and partially embraces the latter, in which the vapor driven off by heat from the yarns is confined and from which it is withdrawn by exhausting means. The hood is constructed with a top wall *10* and side walls *11* forming in effect a wide trunk or box open at its under side, which is disposed in an inclined position so as to overlie the entire length of the space between the size box and drier drum. An end wall is disposed to close its upper end and extend around the outer side of the drier drum to a depth considerably below the axis of the latter. The width of the hood is somewhat greater than the length of the drier drum, and its side walls embrace and enclose the upper part of that drum, as well as the sheet of yarns.

2

Exhaust ducts *12* and *13* are connected with the top wall of the hood at locations suitably disposed to carry away the vapor rising from the yarns. These ducts join a stack *14* by which the vapors are conducted to the outer air and in which is an exhaust fan *15* driven by any suitable means, such as an electric motor *16*. The motor may be mounted in a housing *17* arranged as an extension of the stack below the points of merger therewith of the ducts *12* and *13*, while the exhaust fan is preferably located above such points of merger.

The hot vapors from the yarns coming into contact with the cool top wall of the slasher hood *15* and with the walls of the exhaust ducts are condensed in part. To prevent the condensate thus formed from falling on the yarns and damaging them, I have provided a series of baffles *18* which extend across the full width of the space over the sheet of yarns and are disposed with a slant of the same order as that of the hood but of smaller degree. That is, the baffles are mounted so that the terminal edge of each which is nearer the upper end of the hood is at a higher elevation than the terminal edge which is nearer to the lower end of the hood. Also the baffles are arranged in overlapping relation so that the lower edge of each higher baffle overlaps the upper edge of the next lower baffle, but with a space of substantial height between their overlapping portions. Thus the vapors rising from the heated yarns, together with air drawn into the hood, can pass freely between the overlapping baffles, but any water dripping from the top of the hood or from the exhaust ducts is caught by the baffles.

It may be noted here that the baffles are preferably made of rectangular plates of stiff sheet metal, such as galvanized iron, but with their upper side edge and end edges bent up to form lips or rim walls *19* and *20*, and the lower edge of each (except that of the lowermost baffle) bent down as shown at *21* in Fig. 3. These rim walls confine the water falling on the baffles and guide it to lower baffles, until it reaches ultimately the lowermost baffle *22*.

The baffle *22* differs from the others in that its lower end is upturned to form a lip *23* and thence is turned downward and back for a purpose later described, and that the lips *20a* at the ends of the baffle terminate short of the lip *23*, to provide escape passages or outlets *24*. The water falling on baffle *22*, therefore, is obstructed and deflected and caused to fall into gutters *25* on the side walls of the hood beneath the outlets *24*. The gutters *25* may be connected with drains or arranged in any

other manner suitable to dispose of the water received therein.

The baffles herein described are effective also for disposing of water which condenses on their under surfaces. The condensed water adheres by capillary force and flows to the downturned lip 21 at the lower edge of the baffle before gathering in sufficient quantity to drip. Thus the only dripping of water condensed on the under surfaces of the several baffles is from the lower edge lip of each upper baffle to the next lower baffle in the series. For receiving and conducting away the condensate on the under side of the lowermost baffle 22, the part of that baffle which is turned up to form the lip 23, previously described, is further carried downward and then bent backward and upward until its extreme edge 26 is located beyond the corner or zone 27 at which the lip 23 is bent up. This construction provides a channel 28 open at one side, due to a space left between the edge 26 and bend 27, to receive water condensing on the under side of the baffle, and open at both ends over the gutters 25, whereby it can discharge the water so received into those gutters.

The hood and means for supporting the baffles therein contain novel features of construction as follows: The upright side walls 11, which are preferably of uniform width except at the lower end, and the top wall are preferably made of sheet metal such as galvanized iron and are secured together by locked joints, substantially as shown in Fig. 2. The longitudinal margins of the top wall are bent up at right angles forming ribs 29, and the upper margins of the side walls are extended along the outer sides of the ribs 29 and folded over and pinched against the inner sides of these ribs. At their lower ends the side walls are rolled inward and upward to form the gutters 25, being first cut to an outline which enables such gutters to be located approximately horizontal but with, preferably, a slight downward inclination toward their outer ends. Removable extension wall sections 30 and 31 are provided at each side of the hood. The section 30 is made of a plate of sheet metal similar to that of which the walls 10 and 11 are made, and to it near its opposite side edges are secured hangers 32 and 33 made of strips of angle iron, the upper ends of which are curled over to form hooks 34 adapted to be hung on the beads constituted by the joints between the top and permanent side walls. The hangers 32 and 33 are of unequal length such that, when so assembled with the hood, their lower ends will be at the same level, and the plate 30 is so cut that, when in assembled relation with the hood, its bottom edge will be horizontal and its upper edge 35 will overlap the lower edge of the adjacent permanent side wall 11 and be at an inclination similar to that of the top wall.

The extension wall 31 is made of a triangular plate of like metal to which hangers 36, 37 and 38, of the same nature as the hangers 32 and 33, are secured, whereby the extension 31 may be detachably suspended in the same manner. The upper edge of the plate forming this wall is disposed to overlap the adjacent side wall 11 and has a similar inclination. Permanent side sections 39 and 40 and an end wall embrace and enclose the outer portion of the drum b.

The removability of the side wall extensions 30 and 31 on each side of the hood permits ready access to the space between the permanent walls 11 in which the baffles are located. The ends of

the baffles rest on shelves 41 formed of iron angle sections welded, or otherwise suitably secured, to the inner faces of the walls 11, such shelves having a length slightly shorter than the width of the baffles and being positioned with the inclination prescribed for the baffles. Hooks 42, one of which is shown in Fig. 3, are secured to the baffles in position to overhang the upper ends of the respective shelves when the baffles are placed on the latter. These hooks may be made of short pieces of sheet metal welded or otherwise secured to the under sides of the respective baffles adjacent to their upper corners, and bent down. When a baffle is in place, the shelf on which either end rests is embraced between the hook 42 at that end and the adjacent end of the downturned lip 21. But with respect to the lowermost baffle 22, the curled under part which forms the channel 28 hangs below the lower end of the shelves.

It hardly needs saying that the shelves which support any one baffle are at corresponding levels so that the baffle supported thereon is in an inclined plane of which the elements lying in the width dimension of the hood are substantially horizontal.

The hood may be supported by structural members resting on the floor which supports the slasher or suspended from the ceiling or roof; such supporting or suspension means being omitted from this description since they constitute no part of the present invention and may have various forms.

The descriptive terms used in the foregoing specification are not intended to limit the invention or its field of use to less than the scope embraced by the appended claims, such claims being intended to include all embodiments in which the novel principles of the combination here described may be applied.

What I claim and desire to secure by Letters Patent is:

1. A slasher hood comprising an inclined top wall having an outlet for discharge of air and vapors from the space beneath the hood, permanent side walls connected at their upper edges with the side edges of the top wall by joints which form raised beads, removable extension wall sections having hangers with hooks arranged to engage over said beads and suspend said removable sections in positions wherein the latter extend from and below the permanent side walls, baffle supports on the inner sides of the permanent walls in sloping series generally parallel to the top wall, corresponding supports on the respective walls being at substantially the same height relatively to the top walls, and baffle plates removably mounted on said supports to extend across the spaces between corresponding supports, each baffle being inclined with a slant of the same order as that of the top wall, but less in degree and the lower edge of each upper baffle overlapping the upper edge of the next lower baffle in the series with an intervening space.

2. A slasher hood as set forth in claim 1, in which the several baffle plates have hooks which overlap their respective supports so as to prevent the baffles from sliding off from the supports.

3. A slasher hood as set forth in claim 1, in which the baffle plates have upwardly extending lips at their ends adjacent to, but separate from, the side walls of the hood to prevent water falling on the baffles from flowing between their ends and the side walls.

4. A slasher hood comprising connected top and

side walls adapted to overlie and embrace the upper parts of a slasher and having an outlet for air and vapor, baffle plates extending across the space between the side walls in an inclined series, being substantially horizontal in the direction from side to side of the hood and inclined in the direction transverse thereto with a slant of the same order as that of the series, but less steep, in overlapping relation with spaces between their overlapping portions; the lowermost 10 baffle of the series having an upwardly projecting lip at its lower edge to arrest water flowing down its upper surface and a downwardly, rearwardly and upwardly extending part disposed to form a channel beneath the lower edge located to receive water dripping from such edge, said channel and the angular space between the upwardly projecting lip and the adjacent part of the baffle being open at their ends for discharge of water flowing thereinto.

5. A slasher hood as set forth in claim 4, in which the side walls are provided with gutters on their inner sides disposed below the open ends of the channel and angular space in position to receive water flowing therefrom.

6. A baffle for a drier hood of the character described, comprising a substantially rectangular plate of sheet metal having substantially parallel side margins and substantially parallel end margins transverse to the side margins, one of the 30

side margins and both end margins being upturned to form water-confining lips, and the other side margin being upturned to form a lip and doubled back and curled under the bottom to form a channel having a bounding edge beneath and spaced apart from such bottom.
